UNITED STATES PATENT OFFICE.

CHARLES F. KEMM, OF ALBUQUERQUE, NEW MEXICO, ASSIGNOR OF ONE-THIRD TO
BIBIAN PEREA, OF ALBUQUERQUE, NEW MEXICO.

BOMB.

1,313,300.

Specification of Letters Patent.

Patented Aug. 19, 1919.

Application filed September 18, 1917. Serial No. 181,993.

To all whom it may concern:

Be it known that I, CHARLES F. KEMM, a citizen of the United States, residing at Albuquerque, in the county of Bernalillo 5 and State of New Mexico, have invented certain new and useful Improvements in Bombs; and I do hereby declare the following to be a full, clear, and exact description of the invention, such as will enable others skilled in the art to which it appertains to 10 make and use the same.

This invention relates to improvements in bombs and has for its object to provide a device of this character especially designed 15 to be dropped from aeroplanes and equipped with means whereby the bomb may be exploded at any desired elevation above the ground.

Another object of the invention is the 20 provision of a bomb of this character in which the firing pin which explodes the bomb is released by a cable or other flexible element connected at its end with the aeroplane or other object from which the bomb is dropped, thus permitting of an accurate 25 estimate of the elevation at which the bomb will be exploded after the altitude of the aeroplane has been ascertained.

With these and other objects in view, the 30 invention consists in the novel combination and arrangement of parts which will be fully set forth in the following specification and accompanying drawings, in which:

Figure 1 represents a side elevation of 35 the improved bomb,

Fig. 2 represents a side elevation of the firing pin releasing mechanism removed from the casing,

Fig. 3 represents a plan view of the 40 releasing mechanism,

Fig. 4 represents a longitudinal sectional view therethrough,

Fig. 5 represents a vertical sectional view 45 on the line 5—5 of Fig. 4, and

Fig. 6 represents a perspective view of the safety device for preventing explosion of the bomb by accidental release of the firing pin.

Referring to the drawings in detail, 50 wherein similar reference numerals designate corresponding parts throughout the several views, the numeral 5 indicates a preferred type of bomb or projectile which is adapted to be discharged when exploded by a percussion cap 7 having a base flange

8 confined between a pair of plates 9 and 10 which are rigidly secured to the rear terminal of the bomb 5.

The firing pin releasing mechanism designated generally by the numeral 11 is preferably housed within a casing 12 secured to the shell of the bomb 5, as shown in Fig. 1. The plates 9 and 10 are secured together to firmly clamp the percussion cap 7 by bolts 13 which latter also support a guide 60 plate 14 in spaced parallel relation to the plates 9 and 10. The pointed terminal of the firing pin 15 is slidably received within an aperture 16 formed in the guide plate 14 and the pointed terminal 17 of the firing pin is arranged in axial alignment with the percussion cap 7.

Relatively long spacing bolts 18 are secured at one end to the guide plate 14 and are connected at their opposite ends with a 75 supporting plate 19 which is secured in predetermined spaced relation to the guide plate 14 by nuts 20 fitted upon the threaded terminals of the bolts 18. The upper terminal of the firing pin 15 is slidably engaged within an aperture 21 formed in the supporting plate 19 and is normally retained in downwardly extended position by the tension of a spring 22 confined between the plate 19 and a washer 23 supported upon 80 a pin 24 extending diametrically through the firing pin.

A lever 25 having a curved portion 26 forming a rocker or fulcrum is supported upon the plate 19 adjacent the firing pin 15 90 and is provided with a bifurcated terminal 27 receiving the upper portion of the firing pin and engaging under a head 28 formed in the groove therewith, whereby when the rear portion of the lever 25 is pushed downwardly toward the guide plate 14, the firing pin 15 is supported in elevated or inoperative position. The curved portion of the lever 25 is loosely connected with the plate 19 by a bolt 26.

The outer terminal of the lever 25 is recessed as indicated at 29 to receive the bight portion of a substantially V-shaped retaining member 30, the legs of which are extended through apertures 31 formed in the 105 guide plate 14. The extreme lower terminals of the legs of the retaining member 30 are directly angularly as indicated at 32 and anchored against the under side of the guide plate 14 so as to support the lever 25 in the 110

position shown in Fig. 4. The apertures 31 in the guide plate 14 are amply large to permit swinging movement of the retaining member 30.

5. A ring 33 is positioned upon the diverging legs of the retaining member 30 and is connected with a cable or other flexible element 34 which, when pulled longitudinally, disengages the V-shaped member 30 from the 10 terminal of the lever 25.

15. A guard 35 preferably constructed of spring metal is frictionally held between the plates 10 and 14 by its inherent resiliency and the imperforate body portion of the plate overlies the opening 36 in the plate 10 whereby the pointed terminal of the firing pin 15 is prevented from engaging the percussion cap 7 when the lever 25 is accidentally released.

20. From the foregoing, it is clearly evident that in use, the desired length of cable 34 is let out and as the bomb descends through the air the cable 34 is drawn taut thus exerting a pull upon the retaining member 30, disengaging the bight portion thereof from the recessed terminal 29 of the lever 25 and thus permitting the firing pin 15 to move against the percussion cap 7 under the influence of the spring 22. For safety in transporting 25 the bomb, the guard member 35 illustrated in detail in Fig. 6 is preferably inserted between the plates 10 and 14 and will effectively prevent discharge of the percussion cap 7 by accidental release of the firing pin 30 15 and lever 25.

35. What I claim is:—

1. In combination, a bomb, a percussion cap therefor, means to support said percussion cap, a pair of spaced parallel plates disposed adjacent said percussion cap and having openings in alinement therewith, a spring actuated firing pin slidably mounted 40

in said openings, a firing pin lever fulcrumed on one of said plates, and a V-shaped retaining element engaging the rear 45 end portion of said lever and having its outer portion thereof extending angularly and engaging the other of said plates.

2. In combination, a bomb, a percussion cap therefor, means to support said percussion cap, a pair of spaced superimposed plates disposed adjacent said percussion cap and having openings in alinement therewith, a spring actuated firing pin slidably mounted in the openings of said plates, a firing pin lever formed on one of said plates and having its forward end portion thereof bifurcated and adapted for engagement with said firing pin, and a releasing element connected with said lever and having engagement with 50 55 one of said plates.

3. In combination, a bomb, a percussion cap therefor, a pair of coacting plates, means to support said plates in superimposed relation, means carried by one of said plates for supporting said percussion cap, said plates having alining openings therein, a spring actuated firing pin extending through the openings of said plates and adapted for engaging said percussion cap, a lever fulcrumed to one of said plates and having its forward end portion thereof bifurcated for engaging the rear end portion of said firing pin, and a V-shaped releasing member engaged at its bight portion with the rear end 70 75 portion of said lever and having its outer portion thereof extending angularly and engaging one of said plates.

In testimony whereof I affix my signature in presence of two witnesses.

CHARLES F. KEMM.
